UNITED STATES PATENT OFFICE.

JOHN T. PINE, OF NEW YORK, N. Y.

PUMP-GOVERNOR.

SPECIFICATION forming part of Letters Patent No. 409,500, dated August 20, 1889.

Application filed March 14, 1889. Serial No. 303,231. (No model.)

To all whom it may concern:

Be it known that I, JOHN T. PINE, of the city, county, and State of New York, have invented an Improvement in Pump-Governors; and the following is declared to be a full, clear, and exact description of the same.

My invention applies to the water-supply for hydraulic elevators for buildings and to the general water-supply systems of buildings in which cases, tanks, or receptacles for holding water are located in the upper stories of the buildings or upon the roof; and my invention relates particularly to devices for automatically governing the steam-pump located in the basement by the height of water in the tank at the top of the building, so that when the water in the tank gets low the pump will be started to fill up said tank, and when the water has reached a sufficient height the pump will be automatically stopped. The water to supply this tank on the roof will in a hydraulic-elevator system be taken from a tank or receptacle in the basement, into which the water runs from the stand-pipes with the descent of the elevator, and in a water-supply system the water to supply this tank will be taken from a well or from the water-supply of the place or city in which the building is located.

30 In the drawings, Figure 1 is an elevation and partial section of the devices employed by me. Fig. 2 is a vertical section, in larger size, of the steam-valve.

A represents a stand-pipe passing up 35 through a building from the basement to the top story or roof, and connected to a tank or water-receptacle A', located at the top of the building, and A² denotes the floors of the building. This stand-pipe A may form part 40 of the operating mechanism for hydraulic passenger or other elevator, or it may be connected by branch pipes c at each floor to the basins, closets, &c., in the building for supplying water thereto. This stand-pipe A is 45 connected with the bottom part of the reservoir, and may pass up through the bottom or into the side of the tank, as indicated by dotted lines.

The steam-pump is composed of the water-cylinder B, water-chamber B', steam-cylinder C, plunger D, steam-chest H, discharge-pipe E for the water under pressure, and inlet or suction pipe F, and as these parts are well known they do not require further descrip-

tion. The pipe E extends up through the 55 building, and its upper end bends over the upper edge of the tank to deliver into the tank or reservoir A' the water forced up by the steam-pump. The pipe F is connected to any desirable source of water-supply. 60 This in an elevator system would be a receptacle or tank for the water coming from the piston-cylinders with the descent of the passenger-car, and this in an ordinary water-service system would be a well or city water-supply.

A branch pipe L is connected to the lower end of the stand-pipe A and rises to the cylinder M, in which is a piston N, having a cup-leather fitting the cylinder. The stem d 70 passes up through the cap of the cylinder and its stuffing-box. Upon the stem d is a collar d', and surrounding the stem and resting upon the collar d' are a number of weights i. Connected to the upper end of the stem d are 75 chains or cords k k', which pass over pulleys or rollers l l'. Water fills the branch pipe L and cylinder M from the stand-pipe A, and the weights i on the stem d are to be sufficient to counterbalance the weight of the water in 80 the stand-pipe A, and there is a branch pipe o connected to the pipe L and a pressure-gage r connected to the pipe o, and this gage r indicates the pressure from the column of water in the stand-pipe and reservoir. 85

Connected to the steam-chest H of the steam-pump is a valve-chamber I and steam-pipe G. This valve-chamber I contains the balanced companion valves a a', mounted upon the stem b, which stem is guided in the 90 upper and lower portions of the valve-case, and there are seats e e' for the valves a a'. The upper part of the valve-case that receives the upper end of the stem b is hollow, and there is a rock-shaft g, having a bearing 95 h within this case, and there is a lever-arm f connected to the rock-shaft g, and this lever-arm f is connected to the upper end of the valve-stem b, and upon the rock-shaft g outside of the case is a lever m, upon which is a weight n, 100 and one end of the chain k is connected to the end of this lever m. Steam from the pipe G passes through the valve I into the chest H when the valves a a' are open.

Below the steam-cylinder C there are drip-pipes s, the lower ends of which are connected to a longitudinal drip-pipe t, in which is a valve u and weighted lever v, and one end of

the chain k' is connected to the end of this lever v .

The operation of the mechanism is as follows: When the water in the tank A' has been drawn out for use, so that the tank needs refilling, the weight of the water in the stand-pipe A will have decreased, so as to allow of the descent of the weighted piston N in the cylinder M . This will draw upon the chain k and raise the lever m and open the valves in the valve-chamber I , and admit steam from the pipe G to operate the steam-pump, so that water is forced into the tank A' by the pipe E . As the tank fills with water the pressure due to the column of water in the stand-pipe increases and the weighted piston N is gradually raised and the lever m gradually falls, and when the water in the tank reaches a height at which its pressure is balanced by the weights i , previously regulated, the lever m will have descended fully and the valves a a' be closed to their seats and the supply of steam shut off. These operations are continuously repeated with every fall of water in the tank, thus providing for the automatic regulating of the steam-pump.

The drip-pipes s and t are designed to receive from the steam-cylinder C any water that may collect therein, and said water is discharged into these drip-pipes through the small cocks s' and passes into the pipes s and t . This water accumulates, and the same is periodically drained by the opening of the valve u by the lever v and chain k' with every up-and-down movement of the weighted piston N .

My improved device as herein described is especially adapted for use in large office buildings or apartment houses or large stores where there are either hydraulic elevators or water-supply systems with tanks or water-receptacles in the upper story or upon the roof, and my improvements are very useful, inexpensive, and effective for automatically governing the operations of the steam-pump so that the tank may be replenished whenever necessary.

If desired, the branch pipe L , instead of being connected to the supply stand-pipe A , might be connected to an independent stand-pipe of smaller dimensions from the same tank or receptacle, in which the pressure due to the height of water would operate as effectively as in the supply stand-pipe.

55 I claim as my invention—

1. The combination, with an elevated water-receptacle in the upper part of a building and a steam-pump and pipe therefrom to the tank, of a vertical supply stand-pipe connected with the tank and passing down through the building, a branch pipe connected to the stand-pipe, and a vertical cylinder upon the branch pipe, a piston and rod moving within said cylinder, and variable weights upon the rod to counterpoise the weight of water in the stand-pipe and tank to the desired level, and pulleys and a connection from the weighted piston to

the valve of the steam-pump, whereby the weighted piston is raised and the valve is moved by the increase of pressure due to the rise of the water in the tank and the reverse, substantially as specified.

2. The combination, with an elevated water-receptacle in the upper part of a building and a steam-pump and pipe therefrom to the tank, of a vertical supply stand-pipe connected with the tank and passing down through the building, a branch pipe connected to the stand-pipe, a vertical cylinder upon the branch pipe, a piston and rod moving within said cylinder, and variable weights upon the rod to counterpoise the weight of water in the stand-pipe and tank to the desired level, and the steam-valve chamber I and valve, and the weighted lever m connected therewith, and pulleys, and a chain over the pulleys connecting the weighted piston and weighted lever, whereby the weighted piston is raised and the valve is moved by the increase of pressure, due to the rise of the water in the tank and the reverse, substantially as specified.

3. The combination, with a water tank or receptacle in the upper part of a building, a vertical stand-pipe connected therewith and passing down through the building, and a steam-pump and pipe therefrom to the tank, of a branch pipe connected to the stand-pipe and a cylinder upon the branch pipe, a weighted piston within said cylinder, the steam-valve chamber I and valve, and the weighted lever m connected therewith, and a chain k , and pulleys around which said chain passes, the ends of the chain being connected, respectively, to the weighted piston N and weighted lever m , and a branch pipe o , connected to the pipe L , and a pressure-gage r to indicate the pressure of the weight of water in the stand-pipe and the variations thereof, substantially as set forth.

4. The combination, with a water tank or receptacle in the upper part of a building, a vertical stand-pipe connected therewith and passing down through the building, and a steam-pump and pipe therefrom to the tank, of a branch pipe connected to the stand-pipe and a cylinder upon the branch pipe, a weighted piston within said cylinder, the steam-valve chamber I and valves, and the weighted lever m connected therewith, and a chain k , and pulleys around which said chain passes, the ends of the chain being connected, respectively, to the weighted piston N and weighted lever m , the drip-pipes s and t , connected to the steam-cylinder of the pump, and a valve u , lever v , chain k' , and pulleys i' for the same, one end of the chain k' being connected to the weighted lever v and the other end to the weighted piston N , substantially as and for the purposes set forth.

Signed by me this 8th day of March, A. D. 1889.
